Patented Jan. 18, 1921.

Inventor
Clarence C. Perry

UNITED STATES PATENT OFFICE.

CLARENCE C. PERRY, OF PERCY, ILLINOIS.

MINING-MACHINE.

1,366,096.

Specification of Letters Patent. Patented Jan. 18, 1921.

Application filed April 21, 1920. Serial No. 375,469.

To all whom it may concern:

Be it known that I, CLARENCE C. PERRY, a citizen of the United States, residing at Percy, in the county of Randolph and State 5 of Illinois, have invented certain new and useful Improvements in Mining-Machines, of which the following is a specification.

My invention relates to improvements in mining machines and more particularly to 10 a novel mechanism for rotating and feeding the drill shaft, and a novel means for assembling the said mechanism.

The primary object of the invention lies in the provision of a gear mechanism where- 15 by the rotation of the shaft will be increased while the feeding of the shaft is reduced, thus improving the drill to the extent of in- creasing its strength, durability, and ef- ficiency.

20 A further object of the invention lies in the novel means adapted in assembling the mechanism which permits the parts to be readily removed should they become broken or otherwise inoperative.

25 Other objects and advantages of the invention will be apparent during the course of the following description.

In the accompanying drawings forming a part of this specification and in which like 30 numerals are employed to designate like parts throughout the same,

Figure 1 is a part section and plan view showing in detail the mechanism of my ma- chine;

35 Fig. 2 is a sectional view taken on line 2-2 of Fig. 1 showing the connection of the driving gear with the screw shaft;

Fig. 3 is a detail view partly in section 40 showing the removable sleeve through which the feeding of the shaft is effected;

Fig. 4 is an end view of the sleeve, and

Fig. 5 is a fragmentary view showing the means for connecting the sleeve and gear.

In the drawings, wherein for the purpose 45 of illustration I have shown a preferred em- bodiment of my invention, the numeral 5 designates a frame of substantial rectangular shape having alined apertures 6 and 7 at each of its ends, the aperture 6 being of 50 larger diameter than the aperture 7. Ex- tends inwardly from one side of the frame and formed integral therewith is an arm 8 having an enlarged aperture 9 at its free end which is in alinement with the apertures 6 and 7 of the frame. Projecting laterally 55 from each outer side of the frame is a pin

10 which permits the mounting of the frame upon posts in the usual manner.

A beveled gear 11 has an annular collar 12 which is journaled in the bearing 6, as 60 clearly shown in Fig. 1. The collar of the gear is interiorly provided with a longitudinal rib or spline 13 which fits the longitudinally extending groove 14 formed throughout the length of the screw threaded 65 shaft or bar 15. This bar 15 extends through the apertures of the frame and the arm 8 being provided with any number of threads per inch as may be desired. A frusto conical shaped sleeve 16 having in- 70 terior screw threads 17 is removably secured to the shaft 15, passing through the aperture 9 of the arm 8. The sleeve is provided with diametrically disposed trunnions 16' projecting from its side. A second beveled 75 gear 18 has annular flanges 19 and 20 pro- jecting from each of its sides. The gear 18 is connected to the sleeve by the bayonet shaped slots 18' which are adapted to receive the trunnions 16' forming a breakable 80 connection therebetween. The bore of the flanges is of a conical shape and is adapted to fit tightly over the sleeve 16, as clearly shown in Fig. 1. The upper flange 20 of the gear wheel 18 is journaled in the aper- 85 ture 9 of the arm 8 and projects slightly above the arm having its outer periphery provided with screw threads 21. A locking ring 22 is threaded upon the end of the flange 20 being locked in its adjusted position by 90 the set screw 23.

The sleeve 16 is more clearly illustrated in Figs. 3 and 4 and comprises two sections 24 and 25 which are joined together by the interlocking apertured lugs 26 having a 95 pivot bolt 27 passing therethrough. The section 25 has depending downwardly from its lower peripheral edge adjacent the jointure of the two sections, a lug 28 with an aperture 29 through its lower extremity. The section 24 has depending from its lower 100 peripheral edge adjacent the lug 28, a bifur- cated arm 30 with a screw threaded bolt 31 pivotally joined thereto. This bolt 31 is adapted to pass through the aperture 29 of 105 the lug 28 and adjusts the sections 24 and 25 through the medium of a wing nut 32 which is threaded on the bolt 31.

Midway the length of one side of the frame 5 is a laterally projecting bearing 33 110 having journaled therein a short shaft 34 with a handle 35 rigidly secured to the outer

end thereof by means of the pin 36. Keyed to the inner end of the shaft 34 is a cog wheel 37 having inner and outer cogs 38 and 39 which mesh respectively with the gear 5 wheels 18 and 11, whereby the feed bar or shaft will be rotated and fed forward. Thus it is obvious that upon rotation of the handle 35 the gears 11 and 18 will be revolved in the same direction, said gear 11 10 rotating the shaft at a greater speed than the gear 18 is feeding the shaft. The gear 11 which is provided with the rib or spline 13 causes the rotation of the shaft, while the gear 18 which is mounted upon the internally 15 screw threaded sleeve 16 causes the screw shaft to be fed forward. If during the operation should the parts become worn or broken, the parts may be very easily removed by the operator. This is effected by 20 first removing the locking ring 22 from the flange 20 of the gear 18, which will permit slight longitudinal movement of the gear and by loosening the wing nut 32 which adjusts the sleeve 16, the thread bar 15 may 25 be removed therefrom. It is also a known fact that in the operation of machines of this character the threads are subject to considerable wear owing to the strenuous work to which they are put, and should the 30 threads in the sleeve 16 become useless, a new sleeve could be easily replaced and the efficiency of the machine retained.

It is to be understood that the form of my invention herewith shown and described is 35 to be taken as a preferred example of the same, and that certain changes in the shape, size, and arrangement of parts may be resorted to without departing from the spirit of the invention or the scope of the subjoined claims.

Having thus fully described my invention, what I claim is:

1. In a drilling machine the combination of a frame having alined bearings at each 45 end, a lateral extending bearing between said bearings, a screw shaft passing therethrough, a gear wheel keyed to the shaft, a sleeve detachably threaded to the shaft, a second gear wheel carried by the sleeve and

supported by the lateral bearing, and a 50 double cog wheel meshing with said gears for imparting movement thereto.

2. In a drilling machine the combination of a frame having alined bearings at each end, a lateral projecting bearing betwixt 55 said bearings, a screw shaft passing through the bearings, a gear wheel keyed to said shaft, a sleeve threaded on the shaft, said sleeve being formed of two sections hingedly joined together and held by a turnbuckle, a 60 second gear carried by the sleeve, and a double cog wheel for imparting movement to said gears.

3. In a drilling machine, the combination of a frame having bearings at each end, a 65 lateral projecting bearing betwixt the ends of the frame, a screw shaft passing through the bearings, a gear wheel keyed to the shaft below the top bearing, a removable sleeve threaded on the shaft, a second gear wheel 70 carried by the sleeve and supported by the lateral projecting bearing, a short shaft midway the length of the frame and disposed at a right angle to the main shaft, a double cog wheel carried by said shaft and 75 meshing with said gears, and a handle attached to the shaft for imparting movement to said cog wheels.

4. In a drilling machine the combination of a frame having bearings at each end, a 80 lateral extending bearing between said bearings, a screw shaft passing therethrough, a gear wheel keyed to the shaft, a separable sleeve detachably threaded to the shaft, trunnions extending from opposite sides of 85 the sleeve, a second gear wheel carried by the sleeve, said second gear wheel having a plurality of bayonet shaped slots to receive the said trunnions whereby the gear wheel is removably secured to the sleeve, and a 90 double cog wheel meshing with the said gears for imparting movement thereto.

In testimony whereof, I have affixed my signature in the presence of two witnesses.

CLARENCE C. PERRY.
